UNITED STATES PATENT OFFICE.

WALTER G. ALTHAUS, OF SHAWANO, WISCONSIN, ASSIGNOR OF ONE-FOURTH TO
HOWARD B. RICHMOND, OF SHAWANO, WISCONSIN.

AUTOMATIC STOP FOR SOUND-REPRODUCING MACHINES.

1,420,071.

Specification of Letters Patent. Patented June 20, 1922.

Application filed April 28, 1921. Serial No. 465,121.

To all whom it may concern:

Be it known that I, WALTER G. ALTHAUS, a citizen of the United States, and resident of Shawano, in the county of Shawano and 5 State of Wisconsin, have invented new and useful Improvements in Automatic Stops for Sound-Reproducing Machines, of which the following is a description, reference being had to the accompanying drawings, 10 which are a part of this specification.

The invention relates to automatic stops for sound reproducing machines.

The object of the invention is to provide a stop for automatically stopping the drive 15 of the machine when the playing of the record has been completed without the necessity of setting the stop mechanism.

A further object of the invention is to provide a stop mechanism for sound reproducing machines which is rendered inoperative during the time the tone arm is oscillating, but which becomes operative to set the 20 brake as soon as the tone arm stops swinging, that is, when the needle of the reproducer 25 reaches the last groove of the record.

The invention further consists in the several features hereinafter set forth and more particularly defined by claims at the conclusion hereof.

30 In the drawings: Fig. 1 is a plan view of a device embodying the invention; Fig. 2 is a side elevational view thereof.

The stop mechanism embodying this invention may be built into any of the different 35 types of sound reproducing machines at the time of manufacture, or it may be applied to machines already built in which instance the various parts of the mechanism are mounted on a base plate 3 beneath the record supporting platen 4 where the device is applied to a phonograph.

The numeral 5 designates a turn table post or drive shaft of a talking machine and this is operatively connected with a rotating 45 member 6. This member 6 may be driven from the shaft 5 or from the platen 4, or in any other suitable manner, and as here shown it is driven by a gear 7 meshing with gear teeth 8 formed on the member 6.

50 A brake operating dog 9 is pivotally mounted on the member 6 and is adapted to be moved by a spring 10 into engagement with a bell crank lever 11 connected by a link

12 with a brake lever 13 of usual construction adapted to move into contact with the platen 55 4. It will be understood that the dog may be used to operate any suitable form of brake mechanism supplied with or built into the machine, said dog operating to trip the lever 11 at the proper time to set the brake 60 and thereby stop the machine. Until the record is finished, or until the proper time has arrived to stop the machine, the dog 9 is prevented from engaging the lever 11 by a lever 14 which projects into the path of 65 movement of the dog 9 during the playing of the record.

The lever 14 is pivotally mounted intermediate its ends upon a pivot post 15 and carries a triangular shaped locking pin 16. 70 This pin is adapted to be engaged by the hooked end of a latch 17 which is pivotally mounted intermediate its ends upon the base plate 3. A spring 18 normally acts on said latch 17 to move the hooked end thereof 75 clear of the pin 16, but at a time when the dog 9 moves into contact with the lever 14 a cam 19 on the member 6 acting upon the arm 20 of the latch 17 moves said latch into locking engagement with the pin 16 and thus 80 holds the lever 14 stationary until the dog 9 has been forced in by said lever so as to clear the trip lever 11. This action takes place during the playing of the record, due to means controlling the position of the lever 14 85 with respect to the latch 17.

The means controlling the position of the lever 14 during the playing of the record includes a tension lever 21 which is pivotally mounted intermediate its ends upon a 90 bracket 22 secured to the base plate. One end 23 of this lever is adapted to bear or contact with a stop or projection 24 on the lever 14 on the same side of the pivot as the pin 16, and the other end 25 of said lever 95 carries a spring plate 26 movable toward or away from said end by an adjusting screw 27. A friction plate 28 is secured to a bracket 29 on the oscillating tone arm 30 and is movable between the end 25 and the plate 26 and 100 frictionally engaged therewith so as to swing the lever 21 as the tone arm swings, the movement of said plate 28 causing the end 23 to be forced into engagement with the stop 24 at the proper time to position the 105 lever 14 to be locked in position by the latch

17, as previously described. The screw 27 is used to put the proper tension on the plate 28 so that it will cause lever 21 to function properly and still not put enough tension on the tone arm to cause the reproducer to jump in the grooves of the record. A stop pin 31 limits the movement of the lever 14 in one direction and a stop pin 32 limits the outer swinging movement of the tension lever 21. It will, of course, be understood that the tone arm swings as the needle of the reproducer follows the groove of the record and that the friction plate may be attached to the tone arms of different types or be formed as a part thereof, if desired.

With this construction, as long as the tone arm continues moving and there is a tension on the lever 21, the lever 14 is alternately forced out by the cam 19 and in by the lever 21, thus allowing the machine to continue playing. As soon as the record is finished the tone arm 30 and plate 28 cease moving and the tension lever 21 no longer exerts force upon the lever 14, consequently when the lever 14 is again forced out by the cam 19 and the cam 19 then forces the latch 17 outwardly it causes its bevelled end 17' to engage on the opposite side 16' of the pin 16 to thereby positively hold the lever 14 out of the way until the dog 9 has tripped the lever 11 setting the brake and stopping the machine. As long as the tone arm is travelling on the record, and each time that the lever 14 is forced out by the cam 19, the spring plate 26 is permitted to slip back on the plate 28 in proportion to the movement of the lever 21 by the lever 14.

For the purpose of insuring proper starting and for allowing the usual backward and forward swinging of the tone arm while placing the reproducer on the record without placing the stop mechanism in condition for actuation, I have provided a safety lever 33 for performing the function of the tension lever 21 while starting the machine, and to continue to perform such duties until such time as the friction plate 28 has forced said lever against the action of its spring 34 to such a position that its adjustable end 35 no longer moves into engagement with a projection 36 on the lever 14 after the cam 19 has moved said lever 14 outwardly and as soon as lever 33 ceases to function the lever 21 starts to act, as previously described. The screw forming the end 35 of the lever 33 is provided for adjusting the position at which said lever ceases to function on the inward movement of the tone arm on the record.

The latch 17 and lever 14 have fibre facings which act as silencers when the dog 9 and cam 19 are moved against them.

I desire it to be understood that this invention is not limited to any specific form

or arrangement of parts except in so far as such limitations are specified in the claims.

What I claim as my invention is:

1. In a sound reproducing machine, the combination, with the brake mechanism and the tone arm, of a rotating support, a dog mounted on said support and operatively engageable with said brake mechanism, a lever adapted to be positioned in the path of said dog to prevent its operation during the playing of the record, means controlled by the movement of the tone arm for bringing said lever to an operative position, and means for locking said lever in an operative position while the record is being played at the time when the dog passes said lever.

2. In a sound reproducing machine, the combination, with brake mechanism and the tone arm, of a support, a dog mounted on said support and operatively engageable with said brake mechanism, means for revolving said support concurrently with the record, a lever adapted to be positioned in the path of said dog to prevent its operation during the playing of the record, a pair of tension members controlled by the movement of the tone arm for bringing said lever to an operative position, and means for locking said lever in an operative position while the record is being played at the time when the dog passes said lever.

3. In a sound reproducing machine, the combination with the brake mechanism and tone arm, of a support revolving concurrently with the record, a dog mounted on said support and engageable with a part of said brake mechanism to operate the same, a lever adapted to be positioned in the path of said dog to prevent its operation during the playing of the record, a tension member for positioning said lever, a friction plate on the tone arm engageable with said tension member, a latch for locking said lever in position to prevent the dog from operating, and a cam on said support controlling said latch.

4. In a sound reproducing machine, the combination with the brake mechanism and tone arm, of a support revolving concurrently with the record, a dog mounted on said support and engageable with a part of said brake mechanism to operate the same, a lever adapted to be positioned in the path of said dog to prevent its operation during the playing of the record, tension members operable on said lever during the movement of the tone arm, a frictional plate on the tone arm engageable with said tension members, a latch for locking said lever in position to prevent actuation of the dog, and a cam on said support controlling said latch.

5. In a sound reproducing machine, the combination with the brake mechanism and

tone-arm, of a support revolving concurrently with the record, a dog mounted on said support and operatively engageable with said brake mechanism, a lever adapted 5 to be positioned in the path of said dog to prevent its operation during the playing of the record, a latch for locking said lever in a position to prevent the dog from operating, a cam on said support controlling said 10 latch, and means controlled by the movement of the tone-arm during the playing of the record for positioning said lever for engagement with the latch.

6. In an automatic stop for sound reproducing machines, the combination of a brake actuator and a member for preventing actuation of said actuator until the playing of the record is completed, and a pair of tension levers controlled by the movement of 20 the tone-arm to bring said member to an operative position.

7. In an automatic stop for sound reproducing machines, the combination of a brake actuator and a member for preventing actuation of said actuator until the playing of the record is completed, a pair of tension levers controlled by the movement of the tone-arm to bring said member to an operative position, one of said tension members 25 acting on said member only during starting of the record.

8. In an automatic stop for sound reproducing machines, the combination of a brake actuating member and a lever for preventing actuation of said member until the playing of the record is completed, a pair of tension members controlled by the movement of the tone-arm to bring said lever to an operative position, and means for locking said 40 lever in an operative position while the record is being played at the time when either of said members engages said lever.

9. In a sound reproducing machine, the combination with the brake mechanism and 45 tone-arm, of a rotating support, a dog mounted thereon and operatively engageable with said brake mechanism, a lever adapted to be positioned in the path of said dog to prevent its operation during playing of

the record, means controlled by the movement of the tone-arm for bringing said lever to an operative position, means for positively locking said lever in an operative position while the record is being played at the time when the dog passes said lever, and means 55 for positively locking said lever in an inoperative position when the record is played and at the time when the dog passes said lever.

10. In a sound reproducing machine, the 60 combination with the brake mechanism and tone-arm, of brake actuating means operable on said mechanism at any time, and means including a lever and a pair of tension members controlling the position of said 65 lever and controlled by the movement of the tone-arm to prevent operation of said actuating means until the movement of said arm ceases.

11. In a sound reproducing machine, the 70 combination with the brake mechanism and the tone-arm, of brake actuating means operable on said mechanism at any time, and means including a lever and a pair of tension members engaged by a part of the 75 tone arm and operable while the tone-arm moves to prevent operation of said actuating means until the movement of the tone-arm ceases.

12. In a sound reproducing machine, the 80 combination with the brake mechanism and tone-arm, of a brake actuator operable on said mechanism at any time, a lever adapted to be positioned in the path of said actuator to prevent its operation during the playing 85 of the record, a latch for locking said lever in a position to prevent the actuator from operating, means for controlling said latch, and means controlled by the movement of the tone-arm during the playing of the 90 record for positioning said lever for engagement with the latch.

In testimony whereof, I affix my signature in presence of two witnesses.

WALTER G. ALTHAUS.
